STRIP MATERIAL DISPENSER

Frank G. Ellerman, Evanston, Ill.

Application July 8, 1955, Serial No. 36,878

Term of patent 3½ years

(Cl. D52—2)

The figure is a perspective view of a strip material dispenser, showing my new design.

The undisclosed side of the strip material dispenser is substantially the same in appearance as the side shown in the drawing.

The stamps shown in broken lines are for illustrative purposes only.

The characteristic feature of my design for the strip material dispenser disclosed resides in the roll receptacle portion at the bottom thereof.

I claim:

The ornamental design for a strip material dispenser, as shown and described.
